right

FIGURE 1 is a plan view of a textile fabric or similar article embodying my new design.

A unit is enclosed within the dot-and-dash lines of FIGURE 1 of the drawings, which unit is repeated in regular succession, as indicated by the extensions beyond the unit boundaries.

I claim:

The ornamental design for a textile fabric or similar article, as shown and described.
